UNITED STATES PATENT OFFICE

154,649

DESIGN FOR A SOAP CAKE HOLDER

Thomas N. White, Jr., Franklin, Va.

Application July 8, 1947, Serial No. 140,149

Term of patent 3½ years

(Cl. D4—3)

To all whom it may concern:

Be it known that I, Thomas N. White, Jr., a citizen of the United States, residing in the city of Franklin, county of Southampton, and State of Virginia, have invented a new, original, and ornamental design for Soap Cake Holder, of which the following is a specification, reference being had to the accompanying drawings, forming part thereof, and in which

I claim as my invention:

The ornamental design for a soap cake holder, as shown.

THOMAS N. WHITE, JR.
